R. M. ROOF

OVERHEAD TRANSFORMATION FOR FORDS

Original Filed Sept. 2, 1924

Patented Nov. 17, 1925.

1,561,666

UNITED STATES PATENT OFFICE.

ROBERT M. ROOF, OF ANDERSON, INDIANA.

OVERHEAD TRANSFORMATION FOR FORDS.

Application filed September 2, 1924, Serial No. 735,456. Renewed July 27, 1925.

To all whom it may concern:

Be it known that I, ROBERT M. ROOF, a citizen of the United States, and a resident of Anderson, county of Madison, and State of Indiana, have invented a certain new and useful Overhead Transformation for Fords; and I do hereby declare that the following is a full, clear, and exact description thereof, reference being had to the accompanying drawings, in which like numerals refer to like parts.

This invention relates to a Ford transformation, that is, an internal combustion engine of the L type which is transformed into an overhead valve type motor operable by an overhead cam shaft.

The chief object of the invention is to construct the several parts of a motor of the general character indicated, whereby said parts are readily attachable to an engine commonly called the Ford, for transforming the same into a high speed engine. Such an engine usually requires a pressure lubricating system and a positive circulation cooling system.

The chief features of the invention, therefore, consist in the accomplishment of the foregoing object, by the provision of parts for ready attachment to the Ford engine whereby said engine is transformed into a high speed engine having a pressure lubricating system and a positive circulation cooling system and includes overhead cam shaft means for directly operating overhead valves.

Another feature of the invention consists in the association of the several means for driving the overhead cam shaft means by the usual cam shaft of the Ford engine.

The full nature of the invention will be understood from the accompanying drawings and the following description and claims:

In the drawings, Fig. 1 is a side elevational view of the front portion of a Ford engine equipped with the invention and with several of the parts thereof shown in section to show other parts in detail. Fig. 2 is a front elevational view of the same. Fig. 3 is an enlarged transverse sectional view taken substantially in the plane of line 3-3 on Fig. 1 and in the direction of the arrows. Fig. 4 is an enlarged central sectional view

of a modified form of one portion of the invention.

In the drawings there is illustrated the invention as applied to a Ford motor. This invention includes a plurality of attachments for the present Ford motor or a motor of the general character described. Such a motor consists of a cylinder block 10 provided with an L type detachable head, and herein said head is shown replaced by a head provided with overhead valves having the stems 12 that extend upwardly therefrom and said stems support a spring retainer 13 which retains a coiled spring 14 concentric with the valve stem for normally maintaining the valve in the closed position. The valve stem 12 abuts a tappet cup 15 which is slidably, and if desired, non-rotatably mounted in a supporting plate or base 16. Positioned above said base and rotatably supported in bearings supported by said base is a pair of cam shafts 17 including the meshing gears 18. Positioned forwardly of the forward bearing upon one of the shafts 17 is a sprocket pinion 19 suitably secured to said shaft for rotating the same and thereby rotating both shafts. The shafts 17 carry suitable cams 20 for actuating the tappet cups 15, thereby opening the valves carried by the stems 12. The foregoing construction is disclosed in the co-pending Patent No. 1,509,611, dated September 23, 1924. A cover 21 encloses all of the foregoing cam and valve construction. Said cover 21 must be removed to remove the head from the block.

Suitably secured to the cover and communicating with the cam shaft chamber formed thereby and at one end is a tubular housing herein shown formed of two complementary portions or channels 22 secured together as indicated at 23. Said housing terminates in a flange 24 which in turn is secured to a complementary flange 25 formed upon a casing 26 in turn suitably secured to the upper portion of the crankcase of the Ford engine, and this casting is indicated by the numeral 27. Positioned within the tubular housing 22 is a sprocket chain 28 that is driven by a sprocket gear 29, in turn driven by the timing gear driving shaft

which is the original Ford cam shaft. The housing 22 includes an enlargement 30, and positioned in said enlargement is a finger 31 pivotally supported at 32. Adjustably supported in said enlargement is a pressure member 33 in the form of a bolt secured in adjusted position by the lock nut 34. Pressure of the tautening device 31 upon the chain 28 removes the slack and whip from said chain. It will be readily apparent from the foregoing that the overhead cam shafts 17 are driven in timed relation with the crank shaft 35, since the crank shaft through the usual Ford construction drives the original cam shaft of the Ford, which drives the pinion 29.

In Fig. 4 there is illustrated a modified form of the invention. In this form of the invention the gears 18 are omitted and a single cam shaft 117 having the cams 120 actuate the tappet cups 115 for opening the valves carried by the stems 112. The shaft 117 carries the extension shaft 118 which includes the sprocket teeth 119. In Figs. 1 and 2 the invention is disclosed as of the four valves to the cylinder type, whereas the modification in Fig. 4 discloses two valves to the cylinder type. Either type of valve construction may be utilized as desired.

As shown at the bottom of Fig. 1 the usual timing gear 40 is actuatable by a shaft 41, and this is extended and threaded as at 42. The threaded extension supports a sleeve-like shaft 43, the pin 44 locking the same together, and said sleeve-like shaft 43 carries the pinion teeth 29 for driving the chain. The extension 42 is further extended at 43 and includes a tongue and groove arrangement 46. A shaft 47 has a similar arrangement, and projects forwardly through a gland 48 into a gear housing 49. The foregoing constitutes an outboard bearing for the large timer gear shaft extension. The gear housing 49 includes two channels 50 upon opposite sides and is adapted to support two gears. A cover 51 is associated therewith and with two meshing gears completes the oil pump construction for insuring a pressure lubricating system. This pump requires no special alignment.

Positioned at one side of the cylinder block and communicating therewith, and upon the bracket 60 is a centrifugal type water pump 61 operable by shaft means indicated generally by the numeral 62, which shaft means is also operable by the cam shaft of the original Ford engine in the usual manner. It is to be understood that the base plate 27 replaces the usual Ford base plate, and in general has the same outline as said plate, but is suitably modified as previously pointed out.

The foregoing clearly illustrates that the water pump construction and drive therefor

may be omitted if desired, and also that the oil pump and shaft connection may be omitted if desired, or both may be omitted, and the result will be a transformed overhead valve, overhead cam shaft type of Ford engine. However the addition of the water pump and the oil pump permits operation of the transformation at a much higher speed than normal which results in a more powerful engine of the same volumetric displacement.

The invention claimed is:

1. In an internal combustion engine transformation, the combination of a Ford cylinder block having a crank case and a cam shaft therein, a detachable Ford head replacing overhead valve type head positioned thereabove, an overhead cam shaft, a chamber forming overhead cam shaft enclosing cover therefor detachably positioned above said head, a tubular housing communicating at its upper end with said chamber and at its lower end with the crank case, and a power connection in said tubular housing and operable by a shaft mounted in the original cam shaft bearing for driving the overhead cam shaft in timed relation with the engine.

2. In an internal combustion engine transformation, the combination of a Ford cylinder block having a cooling passage therein and a crank case, a base bracket supported by the same, a timer shaft for the engine and operable thereby, a detachable pump adapted to be included in the cooling system of said engine and included in the timer shaft connection and operable thereby, and a gear pump detachably supported by said base bracket and also included in the timer shaft connection and operable thereby for providing a pressure lubricating supply.

3. In a transformation for Ford engines, the combination of the original timing gear shaft of said engine a sleeve shaft detachably secured thereto and operable thereby, a power connection operable by said sleeve shaft for operating the valves of said engine, another shaft concentrically positioned within said sleeve shaft and having a detachable connection with the original timing gear shaft, and power operable means operable by said concentric shaft.

4. In a transformation for Ford engines, the combination of a replacing overhead valve-type head, the original timing gear shaft bearing, and an extended shaft mounted in said bearing and including driving teeth on the extension for driving the overhead valves of said head.

5. In a transformation for Ford engines, the combination of a replacing overhead valve-type head, the original timing gear shaft bearing, an extended shaft mounted in said bearing and including driving teeth on the extension for driving the overhead

valves of said head, and another and out-board bearing for the extended end of said shaft.

6. In a transformation for Ford engines, the combination of a replacing detachable overhead valve-type head having overhead valves and an overhead cam shaft, cover means therefor and detachably mounted, the

removal of said head requiring previous removal of the cover means, an extended shaft 10 adjacent the crankshaft, and an enclosed drive for the overhead cam shaft operable by said extended shaft.

In witness whereof, I have hereunto affixed my signature.

ROBERT M. ROOF.
